UNITED STATES PATENT OFFICE.

GEORGE S. GATCHELL, OF ROSELLE PARK, NEW JERSEY, ASSIGNOR TO THE SINGER MANUFACTURING COMPANY, A CORPORATION OF NEW JERSEY.

DIFFERENTIAL FEEDING MECHANISM FOR SEWING MACHINES.

1,407,023.

Specification of Letters Patent. Patented Feb. 21, 1922.

Original application filed August 10, 1917, Serial No. 185,446. Divided and this application filed March 18, 1918. Serial No. 223,111.

To all whom it may concern:

Be it known that I, GEORGE S. GATCHELL, a citizen of the United States, residing at Roselle Park, in the county of Union and 5 State of New Jersey, have invented certain new and useful Improvements in Differential Feeding Mechanisms for Sewing Machines, of which the following is a specification, reference being had therein to the accompanying drawings.

This invention relates to sewing machines, more particularly of the multiple-needle type disclosed in the application of George E. Molyneux and George S. Gatchell, Serial 15 No. 40,564, filed July 19, 1915, and has for an object to provide an improved sewing machine feeding mechanism of the differential type wherein the stroke of the fulling feed member may be readily adjusted, while 20 the machine is in operation, to suit the character of the work being stitched; the mechanism operating to secure a uniform stitch-length regardless of the length of stroke of the fulling feed member.

25 A further object of the invention is to provide a differential feeding mechanism which will keep the work closely and accurately under control as it passes from the forward or fulling feed-dog to the main or stitch-length defining feed-dog.

Further objects of the invention will appear from the following description and claims.

The present feeding mechanism is of the 35 type represented in the application of George E. Molyneux, Serial No. 32,269, filed July 5, 1915, although differing therefrom in certain important particulars. In the present instance the main and auxiliary feed-dogs are adjustably connected to their actuating means in such a manner that, in all 40 positions of adjustment, the auxiliary feed-dog will always assume the same definite position, relatively to the needles, at the end 45 of its feeding stroke, preferably with its last tooth slightly in advance of the stitching point, while the main feed-dog will always assume the same definite position at the beginning of its feeding stroke, preferably 50 with its first tooth in the position previously occupied by the last tooth of the auxiliary feed-dog. Additional adjustments of the

feed-dogs relatively to their feed-bars, are provided for varying the above defined positions of the feed-dogs relatively to the stitching point. The machine is, in the present instance, equipped with a presser-foot having a pivoted sole-portion cooperating with the feed-dogs and including spaced toes between which the upturned marginal portions of material are adapted to be presented and fed toward the stitching point.

In the accompanying drawings, Fig. 1 is a side elevation partly in section, of a sewing machine embodying the present invention. 65 Fig. 2 is a similar view of the reverse side of the machine. Fig. 3 is a horizontal section through the standard of the machine above the plane of the work-arm. Fig. 4 is a fragmentary rear elevation of the machine, partly in section, and with the rear cover-plate removed to reveal the mechanism housed within the standard. Figs. 5 and 6 are transverse vertical sections through the work-arm along the lines 5—5 and 6—6, 70 respectively, Fig. 3. Figs. 7 and 8 are side elevations of the feeding mechanism at the ending and beginning points, respectively, 75 of a feeding stroke. Fig. 9 is a front end elevation of the stitch-forming instrumentality.

In the present instance the invention is embodied in a sewing machine constructed substantially in accordance with the disclosure of my copending application Serial No. 85 185,446, filed August 10, 1917, of which this application is a division. The machine frame is formed with a base 1 from which rises the standard 2 carrying the overhanging bracket-arm 3 terminating in the hollow 90 head 4. Secured to the standard 2 is the flanged rearward extremity of the tubular work-supporting arm 5 which is formed with two angularly arranged flat sides 6, 7 (Figs. 5 and 6) and a curved upper side 8, whereby 95 said work-arm is substantially sector-shaped in cross-section. Secured to the front or free end of the work-arm casting is the throat-plate 9. Journaled in and crosswise of the standard 2, above the level 100 of the work-arm and crosswise of the latter, is the main-shaft 10 carrying a pulley wheel 11 and hand-wheel 12 both cast integral with a common hub 13.

The main-shaft is formed with a ball-crank 14 which is embraced by the lower strapped end of a pitman 15 the upper strapped end of which embraces a ball-ended crank-5 pin 16 carried by the crank-arm 17 at the rear end of the needle-actuating rock-shaft 18 which is journaled within the bracket-arm 3 and, at its forward end, carries a crank-arm 19 connected to the reciprocating needle-bar 20 by means of the link 21. Secured to the lower end of the needle-bar 20 is the needle-clamp-block 22 which, in the present instance, is socketed to receive four needles n^1 , n^2 , n^3 and n^4 arranged in a vertical plane transversely of the work-arm 5. 10

Mounted within the end cap 23, in cooperative relation with the needles, is the thread-carrying looper 24; the upper edge of the blade of which is curved concentrically with the curved upper side of the work-arm, Fig. 9, while the lower edge 25 of said blade is but slightly curved or may even be substantially straight throughout a portion of its length. The shank of the looper is 20 secured to the looper-support 26 by a screw 27. The looper-support is clamped to the front end of the oscillating and endwise movable looper-shaft 28 which is journaled within and lengthwise of the work-arm 5 as 25 closely as practicable to the apex of the angle formed by the flat sides 6 and 7 thereof, Figs. 5 and 6, said angle being large enough to accommodate the necessary loop-seizing and shedding strokes of the looper. 30

The looper-operating mechanism is preferably the same as that disclosed in my said copending application. 35

The feeding mechanism is as follows: secured to the main-shaft is the feed-advancing eccentric 29 which is connected by the pitman 30 to the rocker-arm 31 the split hub 32 of which is clamped to the cross-shaft 33 to which shaft is also clamped the split hubs of the main feed-advancing rocker-arm 34 and the auxiliary feed-advancing rocker-arm 35. The main feed rocker-arm 34 is formed with a curved slot 36 in which is adjustably secured a pin 37 connected to one end of a link 38 the opposite end of 40 which is pivotally connected to a lever 39 depending from a fixed fulcrum-pin 40 which extends across and within the standard 2 in parallelism with the main-shaft 10. The lower end of the lever 39 is pivotally 45 connected to the rearward end of the main feed-bar 41 which extends within and longitudinally of the work-arm and, at its forward end, carries a screw-pin 42, Fig. 3, which passes through the slotted shank 43 of 50 the main feed-dog 44 and serves to secure the latter to said bar while permitting adjustment of the feed-dog lengthwise of said bar. When the main feed-dog is at the forward end of its stroke, Fig. 8, the slot 36 55 assumes a position concentric with the point

of pivotal connection between the link 38 and the lever 39 so that the main feed-dog will always assume the same forward position regardless of the position of adjustment of the pin 37 in the slot 36. The main feed-dog 44 is preferably so adjusted on the main feed-bar that the front tooth of said feed-dog will rise into engagement with the fabric in a position somewhat in advance of the needles, as shown in Fig. 8. 75

The auxiliary feed-rocker 35 is formed with a curved slot 45 in which is fitted a pin 46 carried by the rear end of a link 47 the front end of which is pivotally connected to a lever 48 depending from the fulcrum-pin 40. The lower end of the lever 48 is pivotally connected to one end of a link-section 49, the opposite end of which carries a fixed pin 50, and a screw 51, both extending through the slot 52 in the rear end of the link-section 53, the front end of which is pivotally connected at 54 to a bracket 55 screwed to the side of the auxiliary feed-bar 56 which is deeply recessed or grooved at its under side, Fig. 6, to fit about and slide upon the forward end-portion of the main feed-bar 41. The feed-bar 56 carries the auxiliary feed-dog 57. When the auxiliary feed-dog 57 is at the rear end of its stroke, Fig. 7, the curved slot 45 is substantially concentric with the pivotal connection between the link 47 and lever 48 and, as a result, the auxiliary feed-dog will always assume the same position relatively to the needles at the end of its feeding stroke, regardless of the position of adjustment of the pin 46. Preferably the link-sections 49 and 53 are 85 so adjusted that the rear tooth of the auxiliary feed-dog will end its feeding stroke at the same position, somewhat in advance of the needles, at which the front tooth of the main feed-dog begins its feeding stroke. Thus, a uniform stitch-length will be secured regardless of the degree of fulling action of the auxiliary feed-dog. By varying the adjustment of the link sections 49 and 53 relative to each other, the point at which the auxiliary feed-dog 57 ends its feeding 90 stroke, may be varied. 100

The fulling feed may be readily adjusted while the machine is in operation by means of the treadle-controlled lever-arm 58 which is mounted on the rock-shaft 59 fulcrumed on the standard 2 and carrying a lever-arm 60 which is connected by the link 61 to the link 47. Adjustable stop-screws 62 and 63 are provided to limit the range of movement of the lever-arm 58 and a spring 64 connected to the lever-arm 60 and to the frame 110 serves to return the parts to normal position when pressure upon the treadle is released. 120

The main and auxiliary feed-bars are supported within the work-arm on a fulcrum-block 65 which is fitted within the slot 66 in the main feed-bar and is carried by the 130

fulcrum-pin 67 supported, in turn, at the forward end of the feed-lifting lever 68 which is pivoted within the work-arm on the trunnion-screws 69, 69. The said lifting lever 68 is rocked by means of the eccentric 5 70, Fig. 4, carried by the main-shaft and embraced by the upper strapped end of a pitman 71 the lower end of which is pivotally connected to a rearward extension of 10 said feed-lifting lever.

The feed-dogs cooperate with a suitable presser-foot comprising, in the present instance, a sole-piece 72, Fig. 1, pivoted at 73 to the shank 74 secured to the lower end of 15 the usual spring-pressed presser-bar 75.

Having thus set forth the nature of the invention, what I claim herein is:—

1. A sewing machine comprising, in combination, stitch-forming mechanism including a reciprocating needle, and differential feeding mechanism including auxiliary and main feed-dogs arranged respectively in front and in rear of the needle-path, adjustable actuating connections for said front feed-dog permitting variation of its feeding stroke while maintaining a fixed ending point for said stroke relatively to the needle-path, and adjustable actuating connections for said rear feed-dog permitting variation 25 of its feeding stroke while maintaining a fixed beginning point for said stroke relatively to the needle-path.

2. A sewing machine comprising, in combination, stitch-forming mechanism including a reciprocating needle, and differential feeding mechanism including auxiliary and main feed-dogs arranged respectively in front and in rear of the needle-path, adjustable actuating connections for said front feed-dog permitting variations of its feeding stroke while maintaining a fixed ending point for said stroke relatively to the needle-path, and adjustable actuating connections for said rear feed-dog permitting variation 40 of its feeding stroke while maintaining a fixed beginning point for said stroke relatively to the needle-path, and means permitting adjustment of said feed-dogs to vary said ending and beginning points.

3. A sewing machine comprising, a frame including a hollow standard, a hollow work-arm carried thereby and projecting forwardly therefrom and a bracket-arm carried by said standard and overhanging said work-arm, a main-shaft journaled crosswise of said standard and work-arm, a feed-rocker mounted within said standard to oscillate about an axis parallel to said main-shaft and including main and auxiliary feed-actuating 55 rock-arms, main and auxiliary feed-bars extending within and lengthwise of said work-arm, and independently adjustable operative connections between said feed-bars and said rock-arms.

4. A sewing machine comprising, in com-

bination, stitch-forming mechanism including a reciprocating needle, main and auxiliary feed-dogs arranged, respectively, in rear and in front of the needle-path, main and auxiliary feed-bars carrying said feed-dogs, a main-shaft, driving connections between said shaft and said auxiliary feed-bar including a slotted rocker-arm, a link adjustably connected at one end to said rocker-arm, said rocker-arm being curved to assume 75 a position concentric with the opposite end of said link when the auxiliary feed-dog is at the ending point of its feeding stroke, and driving connections between said shaft and the main feed-bar including a slotted 80 rocker-arm, a link adjustably connected at one end to said rocker-arm, said rocker-arm being curved to assume a position concentric with the opposite end of said link when the main feed-dog is at the beginning point 85 of its feeding stroke.

5. A sewing machine comprising, in combination, stitch-forming mechanism including a reciprocating needle and differential feeding mechanism including auxiliary and main feed-dogs arranged respectively in front and in rear of the needle-path, and adjustable actuating connections for said rear feed-dog permitting variation of its feeding stroke while maintaining a fixed beginning 90 point for said stroke relatively to the needle-path.

6. A sewing machine comprising a frame formed with a hollow standard and a hollow work-supporting arm free at one end and at 100 its opposite end joining said standard, main and auxiliary feed-bars extending within and lengthwise of said work-supporting arm, a main-shaft journaled within said standard and extending transversely of the 105 work-supporting arm, a pair of swinging levers fulcrumed within said standard and connected, respectively, with said feed-bars, a feed-rocker fulcrumed within said standard and including main and auxiliary feed-rocker-arms, and adjustable link connections between said feed-rocker-arms and said 110 swinging levers.

7. A sewing machine including in combination a work-supporting arm, a main 115 feed-dog and an auxiliary feed-dog disposed at one end of said work-supporting arm, a feed-bar extending lengthwise of the arm and carrying said main feed-dog, a feed-bar extending lengthwise of the arm and carrying said auxiliary feed-dog, means for raising and lowering the feed-bars, means for imparting backward and forward movements to said bars including a rocking frame at the opposite end of the work-supporting 120 arm from the feed-dogs, means connected to an arm on the rocking frame for oscillating the same, an upwardly projecting arm fixed to said rocking frame and having a segmental slot, a link connecting the main feed- 125 130

bar to said arm, said link having an adjustable connection with said slot, a second arm fixed to said rocking frame and having a segmental slot, a link connecting the auxiliary feed-bar to said second arm, said link having an adjustable connection with said slot, and manually operable devices for

shifting the link connected with said auxiliary bar whereby the throw of the auxiliary bar may be readily controlled by the operator.

In testimony whereof, I have signed my name to this specification.

GEORGE S. GATCHELL.
